US00D997146S

(12) **United States Design Patent** (10) **Patent No.:** **US D997,146 S**
(45) **Date of Patent:** **** Aug. 29, 2023**

(54) **ELECTRONIC DEVICE**

- (71) Applicant: **Samsung Electronics Co., Ltd.**, Suwon-si (KR)
- (72) Inventors: **Chung-Ha Kim**, Suwon-si (KR); **Min-Young Park**, Suwon-si (KR); **Ji-Young Lee**, Suwon-si (KR); **Jong-Bo Jung**, Suwon-si (KR); **Hyok-Su Choi**, Suwon-si (KR)
- (73) Assignee: **SAMSUNG ELECTRONICS CO., LTD.**, Suwon-si (KR)
- (**) Term: **15 Years**
- (21) Appl. No.: **29/816,217**
- (22) Filed: **Nov. 19, 2021**

Related U.S. Application Data

- (62) Division of application No. 29/717,594, filed on Dec. 18, 2019, now Pat. No. Des. 940,119.

(30) **Foreign Application Priority Data**

- Jul. 12, 2019 (KR) 30-2019-0033594

(57) **CLAIM**

The ornamental design for an electronic device, as shown and described.

DESCRIPTION

FIG. 1 is a front perspective view of an electronic device showing our new design according to a first embodiment; FIG. 2 is a front elevation view thereof; FIG. 3 is a rear elevation view thereof; FIG. 4 is a left side elevation view thereof; FIG. 5 is a right side elevation view thereof; FIG. 6 is a top plan view thereof; FIG. 7 is a bottom plan view thereof; FIG. 8 is a rear perspective view thereof; FIG. 9 is a front perspective view of an electronic device showing our new design according to a second embodiment; FIG. 10 is a front elevation view thereof; FIG. 11 is a rear elevation view thereof; FIG. 12 is a left side elevation view thereof; FIG. 13 is a right side elevation view thereof; FIG. 14 is a top plan view thereof; FIG. 15 is a bottom plan view thereof; and, FIG. 16 is a rear perspective view thereof.

(Continued)

The evenly dashed broken lines in the drawings illustrate portions of the electronic device that form no part of the claimed design.

1 Claim, 16 Drawing Sheets
